CLAIM

The ornamental design for hair clip, as shown and described.

DESCRIPTION

FIG. 1 is a perspective view of the hair clip showing my new design;

FIG. 2 is a top plan view of the hair clip;

FIG. 3 is a front elevational view thereof;

FIG. 4 is a bottom view thereof;

FIG. 5 is a right side elevation view thereof;

FIG. 6 is a left side elevational view thereof;

The rear view of the design is the mirror image of the front view shown in FIG. 3.
